UNITED STATES PATENT OFFICE.

GEORGE F. VON MOOS, OF CHICAGO, ILLINOIS, ASSIGNOR OF ONE-THIRD TO EDWARD G. SIGGERS, OF WASHINGTON, DISTRICT OF COLUMBIA.

AUTOMOBILE COVER-ADJUSTER.

1,108,951.

Specification of Letters Patent.

Patented Sept. 1, 1914.

Application filed May 7, 1913. Serial No. 766,213.

To all whom it may concern:

Be it known that I, GEORGE F. VON MOOS, a citizen of the United States, residing at Chicago, in the county of Cook and State 5 of Illinois, have invented a new and useful Automobile Cover-Adjuster, of which the following is a specification.

This invention has reference to improvements in adjusters for automobile covers, all 10 though adapted to other vehicles, and its object is to provide means whereby an automobile cover may be moved from the lowered to the raised position, or the reverse, by a single person without aid.

Automobiles of the larger type with touring bodies are usually provided with a cover of such extent as to overhang both the rear and front seats; while the only relatively permanent connection of the cover with the 15 vehicle body is by way of those bows which are fast to the body adjacent the rear seat, the front bow or bows being customarily detached from the front brackets when it is desired to lower the top or cover, in which case the whole vehicle top is lodged to the 20 rear of the back seat. The result of this construction is that on a touring car the vehicle top is a structure difficult to handle except there be a person on each side of the 25 body to lift the top from both sides simultaneously. This, while an efficient method, is not always possible from lack of help, and it becomes an awkward and tiresome proceeding to raise or lower, and particularly 30 to raise the top when but one person is available for the purpose. Because of this difficulty it often transpires that the occupant or occupants of the vehicle are subjected to discomfort by reason of sunshine 35 or storm rather than attempt to raise the top.

By the present invention there is provided a device which may be of a character to be readily stored in the storage compartment of the vehicle and which may also be readily applied to the front bow of the top in a manner permitting the ready manipulation of the entire top by a single person to raise it to the extended position and apply 40 the lower ends of the front bow to the usual brackets or to remove the front bow from the brackets and ease down the top to the lowered position without fatigue or 45 awkwardness.

The invention will be best understood

from a consideration of the following detailed description, taken in connection with the accompanying drawings forming a part of this specification, with the further understanding that while the drawings show a 60 practical embodiment of the invention, the latter is not confined to any strict conformity with the showing of the drawings, but may be changed and modified so long as such changes and modifications mark no material departure from the salient features of the invention.

In the drawings:—Figure 1 is a perspective view of a fragment of a touring car body of an automobile with the top in the 65 partially collapsed position and showing the invention applied. Fig. 2 is a longitudinal section of a structure embodying the invention with some parts broken and other parts shown in elevation. Fig. 3 is a side view 70 of one of the terminal eye blocks shown in Fig. 2. Fig. 4 is a section on the line 4—4 of Fig. 2 with distant parts omitted.

Referring to the drawings, there is shown a vehicle body 1 which may be taken as typical of any suitable vehicle body, and as indicative of a touring car body of an automobile, although it may represent any other suitable vehicle body, but since the present invention has a greater extent of use in connection with automobiles it will be considered in its application thereto throughout the following description without, however, thereby limiting the use of the invention to the particular type of vehicle.

The body 1 is provided with a top 2 which is indicated in the drawings as following the usual lines of a top designed for a touring car body of an automobile. Such top is customarily provided with rear bows 3 having 80 permanent pivot connection with rear brackets 4; that is, so long as the top remains on the body the rear bows 3 remain attached to the brackets 4. The top is furthermore provided with front bows 5 which may include 85 a canopy bow 6 and the terminal portions of the bow 5 are related to front brackets 7 on the body 1 in a manner to be applied to these brackets or removed therefrom in accordance with whether it is desired to have 90 the top in the elevated or in the lowered position. Such a structure is a very clumsy structure for one person to handle, and it is customary for at least two persons to handle such a top to either raise or lower it.

The front bows 5 have at each free end a laterally projecting pin 8 designed to engage the bracket 7 which is formed with an eye 9 for the purpose, the pin 8 extending through the eye 9 and being there fastened in any suitable manner as by a cotter pin.

By the present invention there is provided a device which may be applied to the pins 8 of the bow 5 in a manner to extend from one pin 8 to the other, so that the bow 5 and the corresponding end of the top may be manipulated from an intermediate portion of the connecting device, and, therefore, be raised and lowered by a single person. This connecting device as shown in the drawings comprises an elongated member 10 and another elongated member 11 which may telescope in the member 10, while at one end of the member 10 there is a block 12 and at one end of the member 11 there is a block 13, each block having a neck 14 introduced into the respective member 10 or 11 which may be tubular and is there held by a rivet 15 or in any other suitable manner. By making the connecting member of two tubes 10 and 11 of such gage that one readily telescopes in the other, the whole device may be made amply strong, and at the same time sufficiently light to permit ready handling.

To make the device of general application the extent of telescoping of one member in the other may be considerable, and in order to hold the two members in adjusted positions that end of the member 10 receiving the member 11 is externally screw threaded as indicated at 16, and a nut 17 is applied to this screw threaded end. Moreover, the threaded end is slit longitudinally, as indicated at 18, preferably on opposite sides, although this is not obligatory, and the nut 17 may have a slight taper, so that as the nut is screwed upon the threaded end 16 the latter will be slightly collapsed, as permitted by the slits 18, and bind firmly on the tube 11. Each block 12 and 13 has an angle arm 19 at the free end of which there is formed an eye 20 of a size to receive the corresponding pin 8 and the eyes 20 are located approximately the same distances from the longitudinal axis of the connecting member made up of the tubes 10 and 11. By milling the exterior of the nut 17 it is readily manipulated by the hand of the operator and sufficient force may be applied to cause the clamping of the tubes as tightly as desired.

Suppose the vehicle top is down, the tubes or hollow rods 10 and 11 are adjusted so that the eyes 20 may be passed over the pins 8 until the ends 19 are brought against the free ends of the bow, and then by tightening the nut 17 or by simply holding the tubes 10 and 11 together in the hands of the operator the top may be moved forwardly by a person standing within the vehicle body

between the sides of the top and pushing it forward the same as is done by two persons on opposite sides of the vehicle usually outside the latter. When the vehicle top has been fully extended the tubes 10 and 11 may be drawn out sufficiently to release the eyes 20 from the pins 8 and the latter are then readily introduced into the eyes 9 of the brackets 7 to be fastened in place, as is customary. To lower the top, the pins 8 may be withdrawn one at a time from the respective eyes 9 and the eye blocks 12 and 13 applied and after the tube 11 has been telescoped into the tube 10 sufficiently the two tubes may be clamped together, thus permitting a ready handling of the top for lowering. While the members 10 and 11 are indicated in the drawings as tubes, they may be otherwise constructed, but usually tubes will be found advantageous over other constructions.

What is claimed is:—

1. A manipulating member for tops or covers of vehicles comprising a telescoping rod or bar having the ends provided with angle eye extensions adapted to the pivot pins of the front bow of a vehicle top.
2. A manipulating member for tops of vehicles having bows designed to be freed from their supports, comprising an extension member of a length to reach between the freed ends of the vehicle-top bow and provided with means constructed to temporarily secure the extension member to said bow.
3. A manipulating member for tops of vehicles having bows designed to be freed from their supports, comprising an extension member of a length to reach between the freed ends of the vehicle top bow and provided with means for engaging said ends to temporarily secure the extension member thereto, said extension member consisting of two telescoping members in telescoping relation and provided with terminal eye blocks each projecting at an angle to the longitudinal axis of the extension member.
4. A manipulating member for tops of vehicles having bows designed to be freed from their supports, comprising an extension member of a length to reach between the freed ends of the vehicle top bow and provided with means for engaging said ends to temporarily secure the extension member thereto, said extension member consisting of two tubular members telescoping one in the other and provided with terminal eye blocks each projecting at an angle to the longitudinal axis of the extension member, the outer tubular member having the end receiving the other tubular member split longitudinally and exteriorly threaded, and a clamp nut applied to the threaded portion.
5. The combination with a vehicle top or cover of bow construction, of an extensible manipulating member extending across the

top between the ends of the front bow thereof and provided with angle and extensions engaging the pivot pins of the said front bow.

5 6. The combination with a vehicle top or cover of bow construction, of an expansible manipulating member extending across the top between the ends of the front bow thereof, and having its ends constructed to detachably engage the pivot pins of said front bow.

10 7. A manipulating member for tops or covers of vehicles comprising an expansible and contractible manipulating member having ends constructed to temporarily engage

the pivot pins of the front bow of the vehicle top.

8. In a vehicle top adjuster, a transferring bar adapted to be placed transverse of the vehicle body, the said bar being made in 20 sections, the end sections being provided with eyes for the reception of the pivot pins of the front bow of the vehicle top.

In testimony, that I claim the foregoing as my own, I have hereto affixed my signature in the presence of two witnesses.
